SPRING ACTION DESK PAD HOLDER

John Potts, Chicago, Ill., assignor to Wilson-Jones Company, Chicago, Ill., a corporation of Massachusetts

Application June 20, 1956, Serial No. 592,634

4 Claims. (Cl. 281—15)

This invention relates to a spring action desk pad holder, and is particularly concerned with means for maintaining a compressor plate in contact with the uppermost sheet of a pad or stack of sheets mounted in a holder and from which individual sheets may be removed from time to time.

The pad holder is designed primarily for calendar pads, but may be used advantageously with memorandum pads or other similar stacks of sheets where the uppermost sheets are torn off and discarded. A compressor plate is positioned across one end of the uppermost sheet and is held thereagainst by spring pressure to prevent accidental separation of the uppermost sheet from the pad. The lower edge of the compressor plate forms a straight edge against which the uppermost sheet may be torn, if desired. The compressor plate is also easily removable so that the uppermost sheet may be removed in its entirety, if desired, instead of being torn across adjacent its top edge.

The chief object of this invention is to provide means for holding a stack or pad of sheets under spring pressure at all times regardless of the height of the stack or pad. The structure by means of which the above and other objects and advantages are attained will be described in detail in the following specification, taken in conjunction with the accompanying drawings, showing a preferred illustrative embodiment of the invention, in which:

Fig. 1 is a perspective view of a pad holder embodying the invention;

Fig. 2 is a cross sectional view, taken along the line 2—2 of Fig. 1;

Fig. 3 is a perspective view of the pad holder with the pad removed;

Fig. 4 is a bottom plan view of the pad holder;

Fig. 5 is an enlarged cross sectional view showing the structure for holding the pad under spring pressure;

Fig. 6 is a top plan view of the compressor plate adapted to fit over the upper edge of the pad; and

Fig. 7 is a fragmentary cross sectional view, taken along the line 7—7 of Fig. 1.

The pad holder comprises a base 2, a compressor plate 3, and spring pressed mechanism for urging the compressor plate towards the base and thereby exerting pressure on a pad or stack of sheet 4 positioned on the base and having the compressor plate lying across the upper edge of the uppermost sheet.

The base 2 is preferably molded of any suitable plastic, although it could be formed from sheet metal, or cast from some light metal, such as aluminum. The base is provided at its lower end with a trough 5 for holding a pencil or the like. A recess 6, formed by a depending cylindrical flange 7, is provided at each side of the base adjacent the trough 5. A cushioning pad 8, of rubber or any suitable composition, fits snugly into each of the recesses 6 to space the lower edge of the holder from the surface of the desk.

2

The upper end of the base has a downwardly extending flange 9 and adjacent side flanges 10 and 11 which cooperate with flange 9 to provide a neat appearance and to substantially conceal the mechanism for holding the compressor plate against the sheets. Flange 9 is provided with integral reinforcing ribs 12. The underside of base 2 has a plurality of integral ribs 13 depending therefrom to reinforce the base. The upper surface of the base is depressed, as indicated at 14, to facilitate positioning of the sheets 4. The sheets are provided adjacent their upper edge with two apertures 15 which register with apertures 16 in the depressed area of the base when the sheets are positioned in said depressed area.

15 The compressor plate 3 is preferably made of plastic to match the base, but may be made of metal. The upper surface of the compressor plate may be decorated in any desired manner as, for instance, by advertising material of the donor, if the pad holder is to be given away for advertising purposes. The compressor plate has a depending flange 17 adapted to abut the upper edges of the uppermost sheets, and a pair of flanges 18 adapted to abut the sides of said sheets. A pair of posts 19 extending through keyhole slots 20 in the compressor plate have enlarged heads 21 adapted to pass through the enlarged portions of the key hole slots. The enlarged heads 21 permit removal of the compressor plate when they are in registration with the enlarged portions of the slots 20 and prevent such removal when they are in registration with the small portions of the slots. The lower ends of the posts 19 which are threaded, as indicated at 22, are adapted to pass freely through apertures 16.

A tubular boss 23 depends from the underside of base 2 in registration with each aperture 16. Only one of these will be described since the structure is duplicated at the other side of the pad holder. The inner diameter of boss 23 is larger than the diameter of aperture 16 so as to loosely receive the upper end of a tubular sleeve 24 provided with a vertical bore 25 threaded to engage the threaded end 22 of post 19. Sleeve 24 is provided with an external annular shoulder 26, and a retaining nut 27 threaded on the lower end of boss 23 has an annular horizontal flange 28 extending inwardly far enough to form a stop adapted to engage shoulder 26 when sleeve 24 is in its lowermost position, and thereby prevent separation of sleeve 24 from boss 23.

The sleeve 24 serves as a supporting leg for the base, and its lower end is counterbored, as indicated at 29, to receive a cushioning pad 30 similar to the pad 8. The upper end of sleeve 24 is recessed, as indicated at 31, to provide a seat for a compression spring 32. The other end of spring 32 bears against the underside of base 2 to exert a constant force urging base 2 upwardly, 55 thereby holding the sheets under compression between plate 3 and base 2.

In order to position a pad 4 in the holder both posts 19 are unscrewed from the bores 25 of sleeves 24. Springs 32 will then force base 2 upwardly until flanges 60 28 abut shoulders 26. After pad 4 is positioned in the depressed area 14 the compressor plate 3 is placed on the upper edge of the uppermost sheet of pad 4 and posts 19 are then inserted through slots 20 and apertures 15 and 16, and then threaded into bores 25. Tightening 65 posts 19 against compressor plate 3 will force base 2 downwardly, depending upon the thickness of pad 4. The height of sleeve 24 above shoulder 26 is less than the depth of boss 23 to allow clearance for the downward movement of base 2. As the individual sheets are removed the base is forced upwardly towards the compressor plate to maintain the compression on the remain-

ing sheets. When flanges 28 abut shoulders 26 so that further upward movement of the base is impossible, the posts 19 may be screwed downwardly into bores 25 to move compressor plate 3 downwardly towards the base to maintain the compression.

Although I have described a preferred embodiment of the invention in considerable detail, it will be understood that the description thereof is intended to be illustrative, rather than restrictive, as many details may be modified or changed without departing from the spirit or scope of the invention. Accordingly, I do not desire to be restricted to the exact structure described, except as limited by the appended claims.

I claim:

1. A pad holder comprising a base, a plurality of sheets positioned on said base, a compressor plate overlying one end of said sheets, a post extending through said compressor plate, sheets and base, a vertically movable sleeve secured below said base, the lower end of said post being threaded in said sleeve, and a compression spring between said base and said sleeve, said spring being effective to move said base and sheets upwardly relative to said post and sleeve to maintain stacks of sheets of varying heights under compression.
2. A pad holder comprising a base, a tubular boss depending from the underside of said base, a sleeve having one end fitting loosely within said tubular boss, a retaining nut secured to the lowermost end of said boss, said nut having an aperture of less diameter than the diameter of the end of the sleeve fitting within said boss, said nut thereby preventing separation of said sleeve from said base, a post extending through said base into threaded engagement with said sleeve, and a spring between said sleeve and said base to urge said base upwardly relative to said sleeve and post, whereby a stack of sheets compressed between said base and the upper end of said post will be maintained under compression as the height of such stack is changed.
3. A pad holder comprising a base, a compressor plate, a plurality of sheets interposed between said plate and

and said base, a pair of posts extending through said compressor plate, sheets and base, a sleeve in threaded engagement with each post, said sleeves being movable in a substantially vertical direction relative to said base, an exterior annular shoulder on each of said sleeves, a pair of retaining nuts secured to said base and engageable with each of said shoulders to prevent separation of said sleeves and said base, and a spring between each of said sleeves and said base to urge said base towards said compressor plate to compress varying numbers of sheets therebetween.

4. A pad holder comprising a base for supporting a plurality of sheets, a boss depending from the underside of said base, said boss having a vertical bore, a retaining nut secured to the lowermost end portion of said boss, said retaining nut having a horizontal flange extending inwardly beyond the outer edge of said vertical bore, a sleeve having an upper end portion positioned within said bore, said upper end portion of said sleeve having an external shoulder positioned within said bore, said sleeve having a threaded vertical bore, a sheet retaining post extending through said base, a stack of sheets mounted thereon, said post being threaded into said last mentioned bore, a compressor plate adapted to be held against the upper end of said post by sheets mounted on said base, and a compression spring interposed between the underside of said base and a portion of said sleeve, said spring urging said base upwardly relative to said sleeve and sheet retaining post to maintain a stack of sheets on said base under compression as said stack is diminished in thickness, until the flange engages the external shoulder on said sleeve.
